[57] CLAIM

The ornamental design for strap device for carrying rolled article, as shown and described.

DESCRIPTION

FIG. 1 is a perspective view of a strap device for carrying rolled article showing my new design;

FIG. 2 is a top plan view thereof;

FIG. 3 is a right side elevational view thereof, the left side elevational view being a mirror image thereof;

FIG. 4 is a bottom plan view thereof;

FIG. 5 is a front elevational view thereof;

FIG. 6 is a rear elevational view thereof; and,

FIG. 7 is a perspective view thereof, shown in it's environmental use.
The broken line showing of connectors and rolled article is for illustrative purpose only and forms no part of the claim.
